CLAIM

The ornamental design for a floating structure for offshore wind power generation as shown and described.

DESCRIPTION

Fig. 1.1 is a perspective view of a floating structure for offshore wind power generation showing our new design;

Fig. 1.2 is a front elevation thereof;

Fig. 1.3 is a rear elevation view thereof;

Fig. 1.4 is a top plan view thereof;

Fig. 1.5 is a bottom plan view thereof;

Fig. 1.6 is a right side elevation view thereof; and

Fig. 1.7 is a left side elevation view thereof.

The broken lines illustrate portions of the floating structure for offshore wind power generation that form no part of the claimed design.
